Primary Examiner — Eric Goodman*Assistant Examiner* — Daniel J Domino(74) *Attorney, Agent, or Firm* — Banner & Witcoff, Ltd.(57) **CLAIM**

The ornamental design for a display screen with graphical user interface, as shown and described.

DESCRIPTION

FIG. 1 is a front view of a display screen with graphical user interface showing the new design; and, FIG. 2 is an alternate view thereof; shown on a device. The broken lines showing text, numbers, and symbols illustrate portions of the article; whereas the device shown in broken lines in FIG. 2 illustrates environmental subject matter. None of the broken lines form part of the claimed design.

1 Claim, 2 Drawing Sheets(56)
